UNITED STATES PATENT OFFICE.

RICHARD E. JONES AND THEODORE P. A. VON THIEN, OF BROOKLYN, NEW YORK,
ASSIGNORS TO ROBERT GAIR COMPANY, OF BROOKLYN, NEW YORK, A CORPO-
RATION OF NEW YORK.

STAMPING ATTACHMENT FOR CARTON-SETTING-UP MACHINES.

1,383,636.

Specification of Letters Patent.

Patented July 5, 1921.

Application filed May 26, 1920. Serial No. 384,269.

To all whom it may concern:

Be it known that we, RICHARD E. JONES, a citizen of the United States, residing at Brooklyn, in the county of Kings and State 5 of New York, and THEODORE P. A. VON THIEN, a citizen of the United States, residing at Brooklyn, in the county of Kings and State of New York, have invented certain new and useful Improvements in Stamping 10 Attachments for Carton-Setting-Up Machines, of which the following is a specification.

This invention relates to mechanism for stamping the date, serial number or other 15 matter upon cartons.

One object of the invention is to provide convenient means for stamping such matter upon the carton during its manufacture without the expense of any separate opera- 20 tion.

Another object is to aid in accomplishing the above object by utilizing the forming block of the carton setting-up machine as the anvil against which the carton is pressed 25 during the stamping.

Another object is to so arrange the mechanism that the bringing about of either of the above two objects will also facilitate the setting up of the carton by the setting up 30 machine.

Other objects of the invention will appear as the description proceeds; and while herein minute details of the invention are de- 35 scribed, the invention is not limited to these, since many and various changes may be made without departing from the scope of the invention as claimed.

In the accompanying drawing, showing by way of example one of the many possible 40 embodiments of the invention,

Figure 1 is a perspective view showing the stamping mechanism in combination with parts of the setting-up machine;

Fig. 2 is an inner-end elevation of the 45 stamp and stamp holder;

Fig. 3 is a side elevation of the stamp holder; and

Figs. 4, 5 and 6 are plan, side elevation 50 and inner-end elevation of a bracket on which the stamp operating mechanism is mounted.

This invention is shown in combination with a carton setting-up machine similar to that shown in the U. S. patent to Scales,

No. 767,445, issued August 16, 1904. This 55 machine comprises an intermittently rotatable vertical shaft 1, a spider fast on the upper end thereof and comprising radially disposed revolving arms 2 each carrying pending from its outer end a mandrel or 60 former block 6 on which card-board cartons are set up, as fully described in said patent.

The attaching means for the new attachment comprises a hanger supporting stud 10 loosely mounted on the upper end of said 65 shaft and provided with a reduced upper end 11 on which is received an opening in the enlarged inner end 13 of a radially disposed hanger arm 14 secured fast on said reduced portion by means of a set-screw 15. 70 A rod support 17 is secured on the outer end of said hanger arm and is provided with a vertical bore receiving fast therein the upper end of a supporting rod 20 having its lower end rigidly fixed on some convenient 75 portion of said setting-up machine.

A stamp-holder bracket 21 secured on the upper part of said rod opposite one mandrel position carries a stamp-holder comprising a horizontal floor 22 and vertical side flanges 80 23 each provided with a longitudinal guide-slot 24. A Robert's numbering or dating stamp 25 of universally known construction is received in said holder and comprises a frame 27 slideable on said floor between said flanges and a stamping mechanism 28 slideable in said frame 27 and to which is secured the outwardly pointing stamp-operating rod 29. Guide-journals 31 are provided on the side of said frame 27 and project outwardly 85 through said guide-slots and have secured thereto retracting springs 33 tensioned between said guide-journals and the rear part of said flanges 23.

A lever bracket 35 comprising a split collar 36 is received on said rod, and is clamped in place by a bolt 37 passing through ears 38. Said bracket is also provided with a limiting lug 41, and a bearing lug 42 on the rear of said collar, the latter receiving a pivot pin 43 on which is fulcrumed an operating lever 44 provided with an intermediate pull-rod-opening 45, and a forwardly projecting beak 46 adapted to engage under said lug 41 for limiting the rearward movement of the operating lever. At the upped end, said lever is provided with a flat operating part 48 adapted to engage a 95 100 105

knob 47 on the outer end of said operating rod 29.

As shown in said patent said setting-up machine also comprises an upright rocking 5 lever 82, shown herein comprising a pair of spaced members 49 having elbow-parts forming inwardly turned upper ends between which rotatably mounted is a turning roller 50 adapted to turn carton-flaps 10 over the lower end of said forming block 6 during the operation of the machine. An anchoring rod 52 mounted between said elbow parts carries a grooved collar 53 on which is received the hooked inner end 54 15 of a pull-rod 55 having its rear portion threaded and passed through said pull rod opening 45 and carrying a nut 57, a pair of washers 58 between said nut and said operating lever 44, and a compression spring 20 60 disposed between said washers.

The operation of the device is as follows:

The form 6 with a carton thereon moves, during the operation of the setting-up machine, to the position of Fig. 1, whereupon 25 the rocking lever 82 moves downwardly and inwardly to turn the flap, as described in said patent, whereupon the pull rod is drawn inwardly compressing the spring and yieldably forcing the operating lever against 30 the knob, and the frame inwardly against the action of the springs 33 until it engages and is stopped by the carton on the block. Continued movement of the operating lever and knob causes the stamping mechanism 35 thereof to move inwardly against the action of its own retracting spring (not shown) until the stamping mechanism is also stopped by engagement with the carton backed by the former block 6 as an anvil 40 therefor, thus stamping the impression on the carton.

The yielding action of the compression spring 60 permits still further movement of the rocking lever 82 and the roller 50, there- 45 by to form the flap of the carton, the stamp 25 meanwhile exerting to an extent a clamping action on the carton somewhat similar to that exerted by the parts 66, 68 and 194 of Fig. 3 of said patent.

50 We claim as our invention:

1. In combination, a shaft; arms fixed on the upper end of said shaft; a former block pending from the outer end of each arm; a stub loosely mounted on the upper end of 55 said shaft; a hanger arm having its inner end fast on said stub; a rigidly supported supporting-rod having its upper end fast on said arm; a stamp-holder fixed on said rod opposite said block; a stamp thereon; and operating means carried on 60 said bracket for pressing the stamp against a carton on the former block.

2. In combination, a shaft; an arm fixed 65 on the shaft; a former block pending from

the outer end of the arm; a hanger arm having its inner end loosely mounted on said shaft; a rigidly supported supporting-rod having its upper end fast on said arm; a stamp-holder fixed on said rod opposite 70 said block; a stamp thereon; and operating means carried on said rod for pressing the stamp against a carton on the former block.

3. In combination, a forming block for cartons; a rigidly supported stamp-holder 75 opposite said block and comprising a floor and side flanges each provided with a longitudinal guide-slot; a stamp comprising a frame 80 slidable in said holder between said flanges, a stamping mechanism slidable in said frame, and an outwardly pointing operating rod; guide-journals, carried on said frame and projecting through said slots; re-tracting springs tensioned between said journals and the rear part of said flanges; and operating means engaging said rod for pressing the stamp against the carton while the block is therein.

4. In combination, a forming block for cartons; a supported stamp-holder opposite 90 said block and comprising a floor and side flanges each provided with a longitudinal guide-slot; a stamp comprising a frame slid- 95 able in said holder between said flanges; guide-journals carried on said frame and projecting through said slots; retracting springs tensioned between said journals and the rear part of said flanges; and operating means for pressing the stamp against the carton while the block is therein.

5. In combination, a forming block for cartons; a stamp holder; a stamp therein; a lever bracket fixed below said holder; an operating lever pivoted on said lever bracket and provided with an intermediate opening, 105 a means for limiting its rearward movement, and adapted at its upper end to engage and operate said stamp thereby to press the stamp to the side carton on said block; an upright rocking lever comprising a pair of 110 spaced members; a turning roller rotatably mounted between said members and adapted to turn carton-flaps over the lower end of said block while the stamp is being pressed against the carton; an anchoring rod mounted between said members; a pull rod having its inner end anchored on said anchoring rod and its rear portion passed through said pull rod opening; a nut on said rear end; and a compression spring disposed between 120 said nut and operating lever.

6. In combination, a forming block for cartons; a stamp holder; a stamp therein; an operating lever provided with an intermediate opening, and adapted to press the stamp to the side of the carton on said block; a rocking lever; a turning roller rotatably thereon and adapted to turn carton-flaps over a face of said block; a pull rod having its inner end anchored on said rocking lever 125 130

and its rear portion passed through said pull rod opening; a shoulder on said rear end; and a compression spring disposed between said shoulder and operating lever.

5 7. In combination, a forming block for cartons; a stamp; an operating lever therefor; a rocking lever; on said machine and comprising a pair of spaced members; a turning roller rotatably mounted on said 10 rocking lever to turn carton-flaps; and a yieldable means disposed between said levers for operating the stamp.

8. In combination, a forming block for cartons; a stamp holder; a stamp therein and 15 comprising a stamp mechanism, an operating rod secured thereto, and a frame carrying said stamping mechanism and adapted to engage and exert a clamping action as the operating rod is pressed upon to operate 20 the stamp to press the stamping mechanism to the carton to stamp an impression thereon while the carton is held by the forming block as an anvil; a turning roller adapted for turning flaps of said carton over a face 25 of said block; a rocking lever carrying said roller; and means operatively connected to said lever whereby said stamp and frame

exert a clamping action on the carton as the flap is being turned.

9. In combination, a forming block for 30 cartons; a stamp holder; a stamp therein and comprising a stamp mechanism, an operating rod secured thereto, and a frame carrying said stamping mechanism, said frame and stamp mechanism being adapted 35 to engage and exert a clamping action upon said carton as the operating rod is pressed upon to operate the stamp to press the frame and stamping mechanism to the carton to stamp an impression thereon while the carton 40 is on the forming block; a turning roller adapted for turning flaps of said carton over a face of said block; a rocking lever for operating said roller and means operatively connected to said lever and engaging said 45 rod whereby said stamp and frame exert a clamping action on the carton as the flap is being turned.
